VACUUM TUBE SYSTEM

Clarence W. Hansell, Port Jefferson, N. Y., assignor to Radio Corporation of America, a corporation of Delaware

Application July 28, 1932, Serial No. 625,288

4 Claims. (Cl. 179—171)

This invention relates to improved vacuum tube circuits such as oscillators, push-pull amplifiers, frequency multipliers, frequency modulators and the like, wherein the vacuum tube filaments or cathodes are heated by alternating current and the other electrodes are supplied with power from rectifiers or other sources of impure direct current containing alternating components of potential and current.

10 It is an object of this invention to provide a simple and inexpensive system to reduce the undesired noise or hum effects caused by the use of alternating current power supply for the vacuum tubes by preventing the addition of current noise arising in various tubes and partially or totally balancing out such addition of current noise.

15 In the past, it has been customary to apply direct current to the vacuum tube filaments or cathodes when such tubes are required for use in high-grade telephone transmitters and furthermore, to provide a high degree of smoothing out of potential variations in the supply for the other electrodes. The equipment required to do this 20 is very intricate, unreliable and expensive.

25 In the past much has been accomplished in reducing the effects of alternating currents on the filaments of vacuum tubes by means of careful tube design. There are also available for 30 low power equipment, vacuum tubes with indirect cathode heaters for which alternating current may be used.

35 There are not, however, available tubes for use in high power transmitters wherein it is possible to use alternating current and still obtain a high quality of output for radio telephone transmitters which have been designed along conventional lines.

40 With my invention it is possible to use existing types of tubes employing alternating current for heating the filaments without exceeding the allowable limits of tube noise required to obtain a high quality of radio telephone output.

45 The principle upon which my invention is based is the general circuit arrangement of the vacuum tube filament heating transformers in such a manner that when alternating currents of different phases are applied to different vacuum tubes in the same system, the difference in time or phase of the noise arising in the various tubes will prevent their addition and, instead, will act to cancel out the undesired noise or hum effects.

50 A further understanding of my invention will

be accomplished by referring to the following drawings in which,

Fig. 1 is a conventional diagram of a push-pull radio frequency amplifier wherein both tubes receive filament power from the same single phase power source;

Fig. 2 is a diagram of a radio frequency push-pull amplifier, in which the filament of each vacuum tube is heated by a separate power supply, each being different in phase;

Fig. 3 is a diagram of an amplitude modulated stage of a radio telephone transmitter when in the filaments of the radio frequency amplifier tubes are supplied with alternating current from two different phases of a three-phase power source, and the three modulator tubes are also supplied from different phases;

Fig. 4 is a diagram of a radio frequency amplifier with a two-phase power supply originating from a three-phase source by using T-connected transformers;

Fig. 5 is a diagram of a radio amplifier and/or frequency multiplier systems with the filament of each successive stage supplied with a current from a different phase;

Fig. 6 is a diagram of an amplifier with a polyphase power supply for heating the filaments of the vacuum tubes with currents from different phases, and, in addition, the alternating current supply of the grid bias rectifiers also 30 come from different phases;

Fig. 7 is a curve indicating very approximately the wave form of the noise or ripple produced in each tube of the amplifier circuit shown in Fig. 1;

Fig. 8 is a curve indicating the wave form and relative amplitude of the noise or ripple produced in the output circuit of Fig. 1, which is due to the addition of the effects in the two tubes;

Fig. 9 is a curve indicating the wave form and relative amplitude of the noise or ripple produced in the output of one tube shown in Fig. 2;

Fig. 10 is a curve indicating the wave form and relative amplitude of the noise or ripple produced in the other tube shown in Fig. 2;

Fig. 11 is a curve indicating the wave form and relative amplitude of the noise or ripple produced in the combined output of both tubes shown in either Fig. 2 or Fig. 3 when the two filament power sources have a 90 degree phase relation;

Fig. 12 is a curve indicating the wave form and relative amplitude of the noise or ripple

produced in the circuit which is shown in Fig. 2 or Fig. 3 when the filaments connect to two phases of a three-phase power source instead of to a two-phase source;

5 Figs. 13, 14 and 15 are curves indicating the wave form and relative amplitude of the noise or ripple produced in each of the three modulator tubes shown in Fig. 3; and

10 Fig. 16 is a curve indicating the wave form and relative amplitude of the noise or ripple produced in the combined output of the three modulator tubes connected as shown in Fig. 3.

15 In Fig. 1 I have shown the conventional and almost universal method used of applying alternating heating current to vacuum tubes in a push-pull radio frequency amplifier. It is to be noted that here both tubes receive filament power from the same single phase power source. With such a system each tube is subjected to 20 changes in impedance as the instantaneous heating current varies. Several of the causes of this impedance change are,

25 First, since the electron emission current drawn from the filament varies approximately in proportion to the 1.7 power or the square of the potential gradient at the filament it follows that an increase in potential at one end of the filament, and a decrease of equal value at the other, will not balance out their effects upon 30 the average current. Due to the approximate square law characteristic of electron flow, the current leaving the negative end of the filament will increase much more than the flow at the positive end of the filament decreases. The result is a distorted wave of fluctuation in anode current and effective anode impedance at a rate corresponding to twice the frequency of the heating current. The wave form of the noise or 35 ripple produced in each tube is approximately 40 like that shown in Fig. 7.

Second, the filament heating current flow sets up a magnetic field around the filament and this field deflects the electrons flowing to the anode. The electron deflections also vary the anode current and tube impedance approximately as 45 shown by the curve in Fig. 7.

50 In addition, the temperature of the filament tends to follow the variations of the alternating current though this effect is usually small in commercial tubes.

55 Therefore, when both filaments are supplied from the same phase, as shown in Fig. 1, the undesired noise and modulations in the two tubes are additive in the amplifier output circuit. They produce undesired phase and amplitude 60 modulation noise in the output of the amplifier as well as distortion of any useful modulation which may be present. If the tubes were part of an oscillator circuit, frequency modulation would be produced. The noise wave form and strength corresponds to the addition of two separate curves such as Fig. 7, and results in a curve as indicated by Fig. 8.

65 According to my invention, if the power supply to the filaments are separated, as shown in Fig. 2, and current supplied to one filament from a source differing in phase from the source used for the other tube, then the noise and distortion due to the filament currents in the two tubes will no longer add directly and may even be made to balance out to a great extent.

70 If the phase difference between the two sources is 90 degrees, as illustrated by Fig. 9 and Fig. 10, then the sum of the effects from the two tubes will be substantially as shown at Fig. 11.

It will be noted that this resultant in the output circuit has only about 20 per cent the amplitude of that obtained when the filament currents to the tubes have the same phase. (Fig. 8). If the power supply is assumed to be 60 cycles, the chief component of hum from each tube is 120 cycles. This 120 cycle component is almost completely balanced out when the two-phase power supply is used. I have noted that the effect upon the various hum frequencies is as follows:

60 cycles	—Not present originally	10
120	Do —Balanced out	
180	Do —Combine 90 degrees out of phase	
240	Do —Still adding	15
300	Do —Combine 90 degrees out of phase	
360	Do —Balanced out	
420	Do —Combine 90 degrees out of phase	
480	Do —Still adding	
540	Do —Combine 90 degrees out of phase	
600	Do —Balanced out	20

In cases where two phase (90 degree) power supply is not available, it is still possible to obtain considerable improvement by connecting each of the two push-pull tubes of Fig. 2 to different phases of a three phase supply. In this case the unbalanced hum is roughly as shown in Fig. 12. In this case the remaining value of peak hum is reduced to only about 42% of that obtained when the filaments are lighted from the same phase.

30 In Fig. 3 there is shown an amplitude modulated stage in a transmitter to which my invention has been applied. In this figure the filaments of the two radio frequency amplifier tubes are supplied from two different phases of a three phase source. There are also shown three modulator 35 tubes, each supplied with filament current from a different phase of the power source. Of course, three groups of tubes could be used. The balancing of hum in the modulator alone is illustrated in Fig. 16. It will be noted that the balancing in the modulator reduces its hum to about 7% of that which it would have had if all tubes had been supplied from the same phase.

40 In Fig. 4 there is shown the Scot or T connected transformers which one may use to supply two tubes of a push pull amplifier with two phase power from a three phase source. Obviously, I may also use T connected transformers to convert two phase power to three phase, where this is required, or I may use other transformer 45 arrangements for control of phase.

45 In addition to balancing the effects of filament hum, I may also apply the same principles to reducing the effect of rectifier ripples in vacuum tube equipment such as shown in Fig. 6 wherein a 50 radio telephone transmitter employs two single phase full wave grid bias supply rectifiers, operated from power sources of different phase, one of these being in the exciter or drive unit and the other in the power amplifier. Originally such 55 transmitters had both bias rectifiers supplied from the same phase of the power supply so that their effects were additive in the outputs of the transmitters. It will be noted that the use of polyphase power for filament heating or rectifier supply 60 introduces a need for more than one regulating device, such as rheostats, in most cases. I may avoid extra complications in operation by placing these devices or rheostats all on one handle or control element so that all are adjusted simultaneously.

65 Although I have shown and illustrated the application of polyphase filament heating power to several circuits such as modulators and push-pull radio frequency amplifiers, it should be under- 70

stood that I have used these only for illustrations. I can apply the same principle in paralleled tubes, in all other circuits or systems such as oscillators, balanced modulators, amplitude modulators, phase 5 modulators, frequency modulators, also all other kinds of vacuum and gaseous tube amplifiers or relays including screen grid tubes, pentodes, frequency multipliers, detectors, vacuum tube voltmeters, etc.

10 Likewise, I may apply my balancing scheme to rectifiers of all kinds so that when their effects are combined in the circuits which they supply, they will not add but will tend to oppose. Also, I have found that, in many cases, by suitable choice or 15 adjustment of power supply phase relations I may balance filament hum with rectifier ripple and vice versa. This is also to be considered a part of my invention.

I claim:—

20 1. A push-pull amplifier system having an input circuit and an output circuit, said system comprising a plurality of electron discharge devices each having a plate, a grid and a filament, a bias rectifier for said grids, separate transformer means for supplying said filaments with alternating currents from a polyphase power supply source, and a phase arrangement of said polyphase power supply source for both transformer means and said bias rectifier whereby undesired 25 hum is balanced out of said output circuit.

2. A push-pull amplifier system having an input circuit and an output circuit, said system comprising a plurality of electron discharge devices each having a grid, a plate and a filament, 30 a plurality of bias rectifiers for the grids of said

electron discharge devices, and separate transformer means for supplying said filaments and said bias rectifiers with alternating current from a polyphase power supply source and a phase arrangement of said polyphase power supply 5 source for both transformer means and said bias rectifier, whereby undesired hum is balanced out of said output circuit.

3. A push-pull amplifier system having an input circuit and an output circuit, said system comprising a plurality of electron discharge devices each having a plate, a grid and a filament, a bias rectifier for said grids, separate transformer means for supplying said filaments with alternating currents from a polyphase power supply 10 source, a separate regulating resistance for each of said transformers, and a phase arrangement of said polyphase power supply source for both transformer means and said bias rectifier whereby undesired hum is balanced out of said output circuit. 15

4. A push-pull amplifier system having an input circuit and an output circuit, said system comprising a plurality of electron discharge devices each having a plate, a grid and a filament, a bias rectifier for said grids, separate transformer 20 means for supplying said filaments with alternating currents from a polyphase power supply source, a separate regulating resistance for each of said transformers and a common control means to adjust each of said regulating resistances simultaneously, and a phase arrangement of said polyphase power supply source for both transformer means and said bias rectifier whereby undesired hum is balanced out of said output circuit. 25

CLARENCE W. HANSELL. 35
